Primary Examiner — Vy N Koenig(74) Attorney, Agent, or Firm — Christine Flanagan(57) CLAIM

The ornamental design for a pop-up gift card holder box, as shown and described.

DESCRIPTION

FIG. 1 is a perspective view of the pop-up gift card holder box of the present invention, in an open position.

FIG. 2 is a left side view of the pop-up gift card holder box of FIG. 1, the right side view being a mirror image thereof.

FIG. 3 is a top down view of the pop-up gift card holder box of FIG. 1.

FIG. 4 is a bottom up view of the pop-up gift card holder box of FIG. 1.

FIG. 5 is a front view of the pop-up gift card holder box of FIG. 1.

FIG. 6 is a rear view of the pop-up gift card holder box of FIG. 1; and,

FIG. 7 is a perspective view of the pop-up gift card holder box of FIG. 1, in a closed position.

The broken lines are for the purpose of illustrating the environment of the design only and form no part of the claimed design.

1 Claim, 5 Drawing Sheets(56)
